TELEVISION RECEIVER

Maximilian Messner, Berlin-Westend, Germany,
assignor to C. Lorenz Aktiengesellschaft, Berlin-Tempelhof, Germany, a company

Application February 29, 1936, Serial No. 66,429
In Germany July 12, 1935

2 Claims. (Cl. 178—7.5)

The invention relates to circuits for the reception of television and has for its object the avoidance of certain disadvantages of arrangements of this type hitherto developed. These disadvantages and the means by which they are avoided are explained in the following description with reference to the accompanying drawing.

Figs. 1 and 2 are diagrams relating to the method of operation of the hitherto known television receiving circuits. Fig. 3 shows an example of the new circuit.

It is well known to rectify the frequency mixture of the picture signals at suitable points, to amplify them and then convey them to the Braun tube. The amplifier situated between the rectifier and the Braun tube is, in this arrangement, extremely complicated as this amplifier must be able to amplify the lowest frequencies of about 25 hertz, and the highest frequencies, nowadays 500,000 hertz, equally well, a requirement which can only be fulfilled with the employment of expensive apparatus. This method further has the disadvantage that when employing an amplifier (low frequency amplifier) inserted between rectifier and Braun tube, and which generally contains coupling capacities, it is impossible to reproduce the mean picture luminosity correctly, since the coupling capacities only transmit alternating potentials for whose mean value the operative point of the Braun tube must be so adjusted that with the picture for "dark", that is, 25% of the maximum amplitude, the Braun tube is controlled just to dark. This arises from the method of so-called gap-synchronisation in which the transmitter in the unmodulated condition operates with a carrier value of 25% of the maximum value. The picture signals are transmitted by increasing, and the synchronising signals by reducing this carrier value, that is, for transmitting the synchronising signals the transmitter is preferably controlled to the zero value.

In Fig. 1 the case is illustrated in which the operative point I on the Braun tube is correctly adjusted. The picture value "dark" modulates the Braun tube to just dark. The characteristic of the Braun tube is designated by K , the value M is the mean value of the alternating potential. The operative point is chosen exactly so that the synchronising signals S are cut off. If the incoming amplitude is greater, that is, if the transmitted picture is made brighter on the average than in Fig. 1, then this operative point is no longer correct. Parts of the incoming frequency mixture which still contain picture modulations

render the control electrode of the Braun tube more negative than is required for the value "dark".

These conditions are shown in Fig. 2. The parts of the picture indicated by hatching are not reproduced. The operative point would have to be displaced from 1 to 2.

In order to avoid this disadvantage it has been proposed to omit the amplifier which, for example, operates in a frequency range from 20 to 500,000 cycles, and to effect the rectification in the Braun tube itself. One modification of this circuit consists in carrying out the rectification, not in the Braun tube, but in a rectifier which is galvanically coupled with the Braun tube. With these circuits the high frequency received by the antenna is converted by the heterodyne principle into an intermediate frequency. The intermediate frequency portion consists of an amplifier coupled by capacity and resistance. An intermediate frequency of 1-1.2 million cycles is chosen. The intermediate frequency with these arrangements is thus near to the highest picture frequency, that is, 500,000 cycles. The consequence is that the rectification is no longer a complete process but a bright line in the Braun tube appears as a string of beads because the half cycles of the intermediate frequency are still visible.

According to the invention an intermediate frequency is chosen which is at least five times the highest picture frequency. In accordance with a further feature of the invention, there is employed as the amplifier, not an amplifier coupled by capacity and resistance, but an amplifier provided with band filters. In the output of the amplifier there is also provided a band filter. The Braun tube is included in the output circuit of this last band filter.

In Fig. 3 all those parts are omitted which serve to supply the feed potentials of the apparatus such as mains apparatus and arrangements for maintaining constant the potentials supplied by the mains apparatus. The tripping apparatus are only shown schematically as they are immaterial for an understanding of the circuit.

The antenna 1 is in the input circuit of a tube 2 , which for example, comprises an octode. 3 is a generator for supplying the heterodyne frequency. The oscillations generated by 3 are mixed in the tube 2 . By the arrangement of the multigrid tube 2 it is ensured that the generator 3 does not radiate into the antenna. The intermediate frequency thus obtained is amplified in the tubes 4 to 7 . The intermediate frequency

stages are coupled to each other by band filters 8 to 11. These filters are similar in construction. In the output of the tube 7 is a band filter 12, which is of the same construction as are the filters 8 to 11. Between tubes 6 and 7 a portion of the amplified intermediate frequency is tapped off and conveyed to control apparatus 13 for effecting synchronization. The tripping apparatus are designated by 14 and 15. By the 10 tripping apparatus 14 the line deflection is effected, which takes place electrostatically, and by the tripping apparatus 15 the picture deflection is effected which takes place electromagnetically. The control apparatus 13 contains an arrangement for segregating the synchronizing impulses from the picture signals and also contains inverting tubes in order to obtain a control of the tripping apparatus which is correct in phase.

The filter 12 contains directly in its output 20 circuit the Braun tube 16. The rectification takes place in the Braun tube itself, that is, by means of the electrode 17 which in the case illustrated is a perforated electrode, but a cylindrical electrode can also be employed. A Braun 25 tube, as is well known, insofar as its rectifying operation is concerned may be regarded as an ordinary tube. Coupling condensers 18 and 19 are necessary, as in the example shown the cathode of the Braun tube is at a high tension potential, whereas its anode is at earth potential, as shown in the drawing. The Braun tube must therefore be blocked in direct potential fashion to the amplifier the cathode of which must be at earth potential and the anode of which must be at high tension potential. This is effected by the condensers 18 and 19, which for example, are of the order of magnitude of 1000 centimeters. The capacity of the Braun tube between cathode and rectifier electrode amounts to about 10 cm. 30 The condensers 18 and 19 must be large with respect to the internal capacity of the Braun tube in order to convey as much as possible of the high frequency potential (intermediate frequency potential) to the Braun tube. In the example shown the potential loss, as will be seen from the capacity values, amounts to 1%. The arrangement is thus very suitable. The condensers 18 and 19 must be made to stand several thousand volts potential, a requirement which

can easily be fulfilled. The Braun tube is included in the output circuit of the filter 12 by the fact that the condensers 18 and 19 which are in series with the internal valve capacity are connected in parallel to the condenser C of the 5 filter 12.

The condensers C are adjustable in order to enable the output circuits of the band filters to be tuned.

The use of an amplifier, coupled by band filters, for the intermediate frequency has the advantage that a very high intermediate frequency can be employed without difficulty. The high intermediate frequency is, as mentioned before, favourable for the picture quality since after the 15 rectification uniform picture lines are formed, that is, not picture lines which are like a string of beads. The construction of the band filter moreover, is simplified by the use of the high intermediate frequency as in television very wide 20 frequency bands have to be transmitted. The higher the intermediate frequency, the smaller is the relative band width, that is, the more simply can the filters be constructed.

The filters 8 to 12 consist in the well known 25 manner of self inductance coils A with high frequency iron cores. In addition, however, ohmic resistances are placed in parallel with the condenser C and the coils A in order to obtain sufficient attenuation, that is, a sufficient band width. 30

What is claimed is:

1. In a television receiver, means for producing an intermediate frequency which is at least five times the highest picture frequency, means for amplifying said intermediate frequency, said amplifying means comprising a multi-stage amplifier provided with band filters for coupling said stages, a Braun tube, and a band filter interconnecting the output circuit of said amplifying means and the Braun tube, this tube 40 being included in the output circuit of said last named band filter.

2. In a television receiver according to claim 1, coils forming part of the band filters and provided with cores of high frequency iron, and attenuating resistances connected in parallel with these coils. 45
